UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

HAY-CARRIER.

1,126,435.

Specification of Letters Patent.

Patented Jan. 26, 1915.

Application filed November 11, 1913. Serial No. 800,368.

To all whom it may concern:

Be it known that I, HENRY L. FERRIS, a citizen of the United States, residing at Harvard, in the county of McHenry and State of Illinois, have invented a new and useful Improvement in Hay-Carriers, of which the following is a specification.

My invention relates to certain new and useful improvements in hay carriers, and is fully described and explained in the specification and shown in the accompanying drawings, in which—

Figure 1 is a side elevation of my improved device, showing the same rigged with rope; Fig. 2 is a central longitudinal section, showing the device rigged with cable; Fig. 3 is a section on the line 3, Fig. 1; Fig. 4 is a similar view with the fork pulley released and lowered, and Fig. 5 is a section on the line 5 of Fig. 2.

Referring to the drawings, 6 is a track upon which is a trip block 7, having a cam surface 8 to raise the trip-member, and stop-surfaces 9 to engage the trip-member when raised to prevent longitudinal movement of the carrier on the track.

10 is the carrier having rollers or wheels 11 running on the track, and to the carrier 10 is swiveled a frame 12. The frame has, at 30 its two ends, sheaves 13 and 14, which are adapted to receive between them a block or fork pulley 15 and to the frame of which is secured a clevis 16 adapted to receive a fork. Pivotal mounted in the frame on longitudinal pivots are locking dogs, each of 35 which has an inturned hook 17 adapted to engage the frame of the block or fork pulley 15, as shown in Fig. 2. Each has, also, an inwardly-projecting finger 18, the two fingers 18 lying in horizontal position when the dogs are in an engaging position. Each dog has also an upwardly projecting part 19. The arrangement is such that when the dogs swing toward locking position, they are limited in their movement by engagement of 40 their upper parts with the frame. When they swing away from engaging position, to the position shown in Fig. 4, they are limited in their movement by engagement of their lower parts with fingers 20 integral with the frame, the construction of said fingers being shown in Figs. 1 and 4.

The trip-member of the device is indicated by 21 and is guided to move vertically in the carriage, the same being provided with in-

wardly-projecting pins 21', which engage the trip-block in accordance with common practice. Swiveled to the lower end of the trip-member 21 is a lever 23 pivoted to the frame which, when the dogs are in engaging 60 position, can lie therebetween.

When the device is strung up with rope, the arrangement is that shown in Fig. 1. The rope is knotted at one end and threaded between one of the sheaves and the frame, 65 the knot operating to limit the movement of the rope, and the free end is led through the block or fork pulley 15 and over the sheave 13.

The operation will be obvious to any one 70 familiar with devices of this character. When the trip-member engages the trip-block, the parts are as shown in Fig. 4. The trip-member is thus elevated, the locking dogs are freed from the lever 23 and the 75 device is held from longitudinal movement on the track. Of course the trip-member cannot fall because the lever 23 then engages with the upper surfaces of the dogs. When the block or fork-pulley 15 is elevated with 80 its load, its frame strikes the fingers 18 on the dogs, swinging the dogs into locking position and permitting the trip-member to drop, and this releases the carrier in the usual manner. When the carrier is returned 85 to the trip-block on the track, the parts will return to released position and the fork-pulley can be drawn down.

If desired, the present structure can be turned end for end through the medium of 90 the swivel or, as is sometimes done, the rope can be pulled through so that the structure can be used from either end. Of course, in operation only one of the sheaves 13 and 14 is effective at the same time.

In certain parts of the country, there is a very large demand for carriers which are operated with wire-cable instead of with rope. This cable is necessarily of much smaller diameter than the rope and it is 100 highly desirable to provide means for using cable and rope interchangeably with the same carrier. This is accomplished in the present structure by providing in each of the three sheaves a narrow central groove 26 105 such as that shown in Figs. 3, 4 and 5. Further to adapt the structure to the use of a relatively-small cable, there is provided at one end of the frame a pivoted stop-plate 24 through which the cable passes, a button 25 110

on the cable engaging therewith to limit its movement.

I realize that considerable variation is possible in the details of the present construction without departing from the spirit thereof, and I do not intend therefore to limit myself thereto, except as pointed out in the following claims, in which my intention is to claim all the novelty inherent in the construction as broadly as the state of the art will permit.

I claim as new and desire to secure by Letters Patent,—

1. In a hay carrier adapted to be operated by means of a rope or cable, an elevating sheave and a fork-pulley, the sheave of the fork-pulley and the elevating sheave being provided on their peripheries with broad rope-receiving grooves, and each having at its center a narrow shallow cable-receiving groove, for the purpose set forth.

2. A hay carrier adapted to be operated with rope of large diameter or with wire-cable of small diameter, having a frame pro-

vided with means for propelling it upon the track, an elevating sheave in the frame, and a fork-pulley provided with a sheave, both of said sheaves being provided on their peripheries with broad rope-receiving grooves and with central shallow cable-receiving grooves.

3. A hay carrier adapted to be operated with a rope of large diameter or with wire-cable of comparatively small diameter having, in combination, an elevating sheave, and a fork-pulley provided with a sheave, said sheaves having broad peripheral rope-receiving grooves, each of which is provided with a central shallow groove to receive the cable, and a perforate member adapted to support one end of the cable, substantially as set forth.

In testimony whereof I have hereunto set my hand this 21st day of October, 1913.

HENRY L. FERRIS.
